DEEP WELL PUMP

Filed July 10, 1951

UNITED STATES PATENT OFFICE

2,669,939

DEEP WELL PUMP

Richard N. Vickers, Smackover, Ark.

Application July 10, 1951, Serial No. 236,033

2 Claims. (Cl. 103—155)

1

This invention relates to an improved deep well pump of the general character disclosed in Patent No. 2,048,085, issued to me July 21, 1936.

An object of the invention is to provide a pump wherein the pump assembly may be pulled from a well without pulling the well tubing therefrom, and wherein said assembly will require no special parts at the foot of the well tubing to accommodate said assembly, so that the assembly may be installed in any well having a tubing conforming to usual practice.

Another object of the invention is to provide a pump assembly wherein provision will be made for the flow through the assembly of the liquid being pumped, independently of any surrounding jacket or nipple for said assembly, so that any necessity for providing a tight seal at any point between the assembly and the jacket or nipple, except the usual packing at the foot of the well, will be avoided.

And the invention seeks, as a still further object, to provide an assembly embodying a valve cage and separate bypass unit which cooperate to provide a receiving chamber for the liquid being pumped, wherein said unit will be provided with straight, vertical bypass passages through which said liquid may be freely lifted from said chamber into the standing tube or barrel of the pump, as the pump plunger moves upwardly, wherein said unit will be further provided, in combination with said vertical, straight passages, with inclined outlet passages for discharging said liquid into the well tubing, as the pump plunger moves downwardly, and wherein said outlet passages will be sloped upwardly and outwardly radially of said unit to freely conduct the liquid from said chamber into the well tubing.

Other and incidental objects will appear during the course of the following description of the invention, and in the drawings:

Figure 1 is a vertical sectional view through my improved pump.

Figure 2 is an enlarged, fragmentary, vertical section particularly showing the bypass unit and standing valve cage.

Figure 3 is a transverse section on the line 3—3 of Figure 2.

Figure 4 is a transverse section on the line 4—4 of Figure 2.

In the drawings, I have shown my improved pump in conjunction with a conventional well tubing 10, at the lower end of which is provided the usual nipple 11 connected with the tubing by a collar 12. As will be observed, the nipple 11 is of less diameter than the tubing.

2

Disposed in the lower end portion of the nipple 11 is a cup tube 13 carrying suitable cups 14 which serve to pack off the well pressure between the tube and nipple, and screwed onto the upper end of said tube is a tubular valve cage 15. Clamped between the tube and cage is a seat 16 upon which normally rests a standing valve 17, and formed on the inner circumference of the chamber for said valve is an annular series of spaced, vertical ribs 18 adapted to limit lateral play of the valve and guide the valve in its vertical movement beneath a stop spider 19 at the upper end of said chamber.

Screwed onto the upper end of the cage 15 is 15 a bypass unit 20 which is provided at its lower end with a recess 21 cooperating with a similar recess 22 in the upper end of the cage to form a receiving chamber 23 between the two parts. At its upper end, the unit 20 is provided with a 20 recess 24, and formed through said unit, as best seen in Figures 3 and 4 of the drawings, is a series of vertical, circumferentially spaced, bypass passages 25 which lie parallel to the axis of said unit and connect the chamber 23 with the recess 24.

The unit 20 is cored axially to provide an outlet chamber 26, and leading from the upper end portion of said chamber through the periphery of said unit is a pair of oppositely disposed, inclined outlet passages 27 which slope upwardly 30 and outwardly radially of the unit. Disposed within the chamber 26 is a valve seat 28 retained by a tubular plug 29 screwed into the lower end portion of said chamber, and normally resting upon said seat is an outlet valve 30. Formed on the unit 20 immediately below the upper ends of the passages 27 is an annular flange 31 which rests upon the upper end edge 35 of the nipple 11 and supports the pump assembly in operative position within the well tubing 10.

Screwed into the upper end of the bypass unit 20, as best seen in Figure 1 of the drawings, is a tubular stem 32 onto which in turn is screwed a head 33 provided axially with a socket 34 having a left hand thread. Screwed at its lower end to the head 33 is a standing tube 35 which forms the barrel of the pump, and reciprocable in said tube is a plunger 36. Screwed into the lower end of the plunger is a stud 37 adapted to fit the socket 34 and provided with a left hand thread to engage the thread of said socket.

Screwed onto the upper end of the plunger 36 is a head 38 to which the usual pump rods are attached, and screwed onto the lower end of said head 55 is a sleeve 39 which telescopically fits the

standing tube 35 snugly. An annular chamber 40 is thus defined between the sleeve and plunger at the upper end of the standing tube.

Formed in the upper end of the plunger 36 is an axial passage 41 at the lower end of which are radial ports 42 communicating with the chamber 40, and formed in the head 33 to communicate with said passage is an aligned valve chamber 43 at the upper end of which are radial ports 44 opening through the periphery of the head. Clamped between the head and plunger is a valve seat 45, and normally resting upon said seat is a relief valve 46. Thus, any liquid trapped in the chamber 40 may flow through the ports 42, passages 41, valve chamber 43, and ports 44 to emerge into the well tubing 10.

In operation, upward movement of the plunger 36 will open the standing valve 17 and liquid will be lifted through the tube 13 and cage 15 into the receiving chamber 23 between the cage and bypass unit 20, whence the liquid will rise through the passages 25 of said unit and through the stem 32 and head 33 into the standing tube 35. As will be perceived, the passages 25 of the bypass unit provide a straight, unobstructed course for the upward flow of the liquid. Upon the return downward movement of the plunger 36, the standing valve 17 will close and liquid in the standing tube 35 will be forced back through the passages 25 into the receiving chamber 23, whence the liquid will be forced to open the outlet valve 30 and flow upwardly through the outlet chamber 26 and outlet passages 27 into the well tubing 10 to rise to the surface of the well. As the passages 27 are inclined upwardly, the angularity thereof will offer a corresponding minimum retardation to the upward flow of the liquid. Thus, in the present instance, by combining the use of the straight, vertical passages 25 with the inclined passages 27 in the bypass unit 20, maximum efficiency of the pump assembly is obtained.

It is to be noted that, in the present instance, the receiving chamber 23 makes provision within the assembly itself, independently of the nipple 11, for the flow of liquid being pumped, so that a conventional nipple may be employed instead of a similar special part adapted to cooperate with the assembly to provide a like chamber. Thus, the present assembly may be readily installed in any well using a conventional tubing, without the necessity for first pulling the tubing to install a special nipple at the foot of the tubing. It is further pertinent to observe that the provision of the chamber 23 between the cage 15 and bypass unit 20 also renders it unnecessary to provide a seal between the bypass unit and the nipple 11 at the flange 31, so that it is possible to rest said flange against the upper end edge of said nipple without any special joint between the parts.

To withdraw the pump assembly from the tubing 10, the plunger 36 is lowered and rotated to the left to engage the stud 37 in the socket 34 of the head 33, when the assembly may be pulled upwardly. Similarly, by engaging the stud in said socket, the assembly may be lowered into the tubing and installed, when the plunger may be freed by rotating it to the right.

Having thus described my invention, I claim:

1. In a deep well pump, a pump assembly including a bypass unit provided at its lower end with a recess and having an external supporting flange, said unit being cored axially to provide an outlet chamber intersecting said recess and

being formed with an inclined outlet passage sloping upwardly from said chamber to open through the periphery of said unit at a point above said flange, an outlet valve mounted in said outlet chamber at the lower end of said inclined outlet passage and controlling back-flow through said outlet passage, an imperforate valve cage connected to the lower end of said unit and open at its ends but closed at its periphery, a standing valve mounted in the cage near the lower end thereof and controlling back-flow through the cage, the upper end of the cage being provided with a recess registering with the recess at the lower end of said unit to provide a receiving chamber communicating with said outlet chamber but closed by the cage to exclude the return of pumped liquid through the periphery of the cage into said receiving chamber, said unit being provided internally with a vertical bypass passage leading from the upper end of said unit into said receiving chamber, and means in communication with the upper end of said unit and operable to pump a liquid upwardly through said assembly as well as force the pumped liquid back through said assembly for discharge at a point of exit.

2. In a deep well pump, a well tubing, a nipple attached to the lower end of said tubing and of less diameter than the diameter of the tubing to expose the upper end edge of the nipple, a pump assembly including a bypass unit provided at its lower end with a recess and having an external flange resting upon said edge of the nipple for removably supporting the assembly in operative position within said tubing and nipple, said unit being cored axially to provide an outlet chamber intersecting said recess and being formed with an inclined outlet passage sloping upwardly from said chamber to open through the periphery of said unit at a point above said flange and communicate with the lower end of the well tubing, an outlet valve mounted in said outlet chamber at the lower end of said inclined outlet passage and controlling back-flow through said outlet passage, an imperforate valve cage connected to the lower end of said unit, a standing valve mounted in the cage near the lower end thereof and controlling back-flow through the cage, a cup tube connected to the lower end of said cage and provided with a cup to coact with said nipple for sealing off hydrostatic pressure in the well tubing and the nipple at a point above the lower end of said cup tube, said cage being open at its ends but closed at its periphery to communication with the nipple above the point of seal of said cup with the nipple, the upper end of the cage being provided with a recess registering with the recess at the lower end of said unit to form a receiving chamber communicating with said outlet chamber as well as communicating with said nipple solely through the lower end of said cup tube, a standing tube connected with the upper end of said unit, said unit being provided internally with a vertical bypass passage connecting said standing tube with said receiving chamber, and a plunger reciprocal in said standing tube.

RICHARD N. VICKERS.
